United States Patent Office

Des. 220,772
Patented May 18, 1971

220,772

PULLER

Harold V. Hawkins, 4985 Meadowbrook Road; and Ralph A. Dick, 8667 Bonview, both of Williamsville, N.Y. 14221; and John Wendel, 42 Susan Lane, Cheektowaga, N.Y. 14225

Filed Feb. 5, 1970, Ser. No. 21,286

Term of patent 14 years

Int. Cl. D8—02

U.S. Cl. D41—1

Des. 220,772

PAGE 2

Fig. 2.

Fig. 5.

Fig. 7.

Fig. 8.

FIG. 1 is a front elevational view showing our puller;
FIG. 2 is a rear elevational view thereof;

FIGS. 3 and 4 are opposite end perspective views thereof;

FIG. 5 is a front elevational view similar to FIG. 1 but showing the puller modified to permit a double reeving operation;

FIG. 6 is a rear elevational view of the modified puller shown in FIG. 5; and

FIGS. 7 and 8 are opposite end perspective views of the modified puller shown in FIG. 5.

The broken lines are for illustrative purposes only.

We claim:

The ornamental design for a puller, as shown and described.
